SHOE BRUSH

Robert Carl McCord, Florence, Mass., assignor to Pro-
Phy-Lac-Tic Brush Company, Florence, Mass., a cor-
poration of Delaware

Filed Mar. 14, 1966, Ser. No. 1,448

Term of patent 14 years

(Cl. D9—2)

FIG. 1 is a side elevational view of a shoe brush showing our new design;

FIG. 2 is a top plan view of the shoe brush shown in FIG. 1;

FIG. 3 is a right end elevational view of the shoe brush shown in FIG. 1; and

FIG. 4 is a top perspective view of the shoe brush shown in FIG. 1.

The left end, not shown, is substantially like the right end.

It is to be understood that the broken lines representing the bristles are intended to cover the entire area indicated thereby.

The dominant features of my design reside in the portions shown in full lines.

I claim:

The ornamental design for a shoe brush, as shown and described.
